UNITED STATES PATENT OFFICE.

WILLIAM MACKIE, OF SIDNEY MINES, CAPE BRETON, NOVA SCOTIA, CANADA.

WRENCH.

1,025,703.

Specification of Letters Patent.

Patented May 7, 1912.

Application filed December 9, 1911. Serial No. 664,848.

To all whom it may concern:

Be it known that I, WILLIAM MACKIE, subject of the King of Great Britain, residing at Sidney Mines, Cape Breton, Nova Scotia, Canada, have invented certain new and useful Improvements in Wrenches, of which the following is a specification, reference being had therein to the accompanying drawings.

10 This invention relates to wrenches, and the objects of my invention are to provide a quick-acting monkey wrench having an adjustable jaw that is automatically opened relatively to the fixed jaw of the wrench 15 when said adjustable jaw is released, and to provide simple and effective means for locking the adjustable jaw relatively to the fixed jaw of the wrench.

Other objects of my invention are to provide a wrench that is strong and durable 20 and highly efficient for gripping the flat facets of a nut, and to accomplish the above results by a combination of mechanical elements that will be hereinafter specifically 25 described and then claimed.

Reference will now be had to the drawings wherein like numerals denote corresponding parts throughout the several views, in which—

30 Figure 1 is a side elevation of the wrench. Fig. 2 is a longitudinal sectional view of the same. Fig. 3 is a horizontal sectional view taken on the line III—III of Fig. 2. Fig. 4 is a similar view taken on the line 35 IV—IV of Fig. 2. Fig. 5 is a perspective view of the detached locking member, and Fig. 6 is a perspective view of the detached releasing member.

The handle of the wrench comprises two 40 sections 1 having the outer ends thereof enlarged and provided with longitudinal confronting recesses 2 and longitudinal confronting grooves 3. Mounted upon the outer ends of the handle sections is a stationary 45 jaw 4, said jaw having a socket 5 to receive the outer ends of the handle sections. The jaw 4 is secured to said sections by a transverse pin 6. The jaw 4 is provided with an opening 7 in communication with the 50 confronting grooves 3 of the handle sections 1. Extending through the opening 7 into the confronting grooves 3 is a shank 8 having a jaw 9, said jaw co-operating with the jaw 4 in gripping the facets of a nut. The shank 8 has a longitudinal groove 10, and 55 located in said groove is a coiled retractile

spring 11, said spring having the inner end thereof connected to an eye 12 carried by the shank 8, and the outer end of the spring is connected to an eye 13 carried by the jaw 4 within the socket 5. The groove 10 is formed in the front side of the shank 8 and extends from the jaw 9 to a point in proximity to the inner end of the shank.

Located in the inner end of the shank 65 is a handle 14 that is secured in the shank by a transverse pin 15. The handle 14 extends through a slot 16 in the front sides of the handle, said slot being formed by cutting away the confronting front edges 70 of the handle section, as best shown in Fig. 4 of the drawing.

The rear side of the shank 8 is provided with transverse teeth 17 and engaging said teeth are the teeth 18 of a pivoted locking 75 member 19. The locking member 19 is pivotally mounted in the confronting recesses 2 by a transverse pin 20, the pivoted end of said member being located in the outer end of the recesses 2. The inner end of the locking 80 member has a notch 21 to receive the ends of a releasing member 22. The releasing member 22 is pivotally mounted by a pin 23 in an opening 24 provided therefor in the handle sections 1, said opening being 85 formed by cutting away the confronting sides of said section at the rear side of said handle.

Located within the confronting recesses 2 are bow springs 25, said springs having the 90 ends thereof mounted in the walls of the recesses 2 and in the rear sides of the locking member 19, said member having sockets 26 to receive the ends of the bow springs 25. These springs are adapted to normally hold 95 the locking member 19 in engagement with the shiftable shank 8 of the wrench, and it is preferable to locate one of the springs at a point intermediate the locking member 19, and the other spring adjacent to the 100 free end of said locking member, whereby the tension of said springs will be distributed over the locking member 19.

In operation, the wrench is used for rotating nuts or objects having flat facets. 105 When the releasing member 22 is pressed toward the handle, the locking member 19 is moved out of engagement with the shiftable shank 8, and then the spring 11 located within the groove 10 of the shank, shifts 110 the shank 8 outwardly, opening the jaw 9 relatively to the stationary jaw 4. When

the releasing member 22 is released, the bow springs 25 immediately place the locking member 19 in engagement with the teeth 17 of the shank 8, locking this shank in the handle sections. By gripping the handle 14, the shank 8 can be shifted into the handle to close the jaw 9 with respect to the jaw 4, this operation taking place when it is desired to place the jaws 4 and 9 in engagement with the nut. The teeth 17 of the shank 8 recede over the teeth of the locking member 19, said member yielding, together with the releasing member 22, to permit of the shank 8 being shifted into the handle.

15 The wrench is made of light and durable metal, and I reserve the right to construct the gripping surfaces of the jaws 4 and 9, whereby said jaws may be used for gripping a pipe or structure having curved or round-

20 ed surfaces.

What I claim is:

A wrench embodying handle sections secured together and having the confronting sides thereof provided with confronting 25 grooves and confronting recesses, a jaw mounted upon the outer ends of said handle sections and having an opening formed

therein alining with the confronting grooves of said handle sections, a shank slidably mounted in said handle sections and having 30 the rear sides thereof toothed, the front side of said shank having a longitudinal groove formed therein, a jaw carried by the outer ends of said shank, a handle carried by the inner ends thereof and protruding from the 35 front sides of said handle sections, a coiled retractile spring located within the groove of said shank and having one end thereof connected to said shank, and the opposite end thereof connected to the jaw of the 40 handle sections, a pivoted locking member arranged in the recesses of said handle sections and normally engaging said shank and a releasing member pivotally mounted between said handle sections and engaging 45 the inner ends of said locking member for shifting said member out of engagement with said shank.

In testimony whereof I affix my signature in the presence of two witnesses.

WILLIAM MACKIE.
